PERFORATOR FOR WELL PIPES

John C. Luccous, Dallas, Tex.

Application November 27, 1941, Serial No. 420,614

17 Claims. (Cl. 164—0.4)

This invention relates to new and useful improvements in perforators for well pipes.

One object of the invention is to provide a perforator which may be lowered into a well pipe and operated therein by means of a flexible line or wire to perforate the wall of the pipe.

An important object of the invention is to provide an improved perforator operable by means of a flexible wire or line and which has means providing for accurate location of the perforations in the well pipe at any desired elevation therein.

A further object of the invention is to provide, in a perforator of the type described, means for positively disclosing whether the cutter points have been moved to their fully expanded position, thus indicating that the desired perforations in the well pipe have been made.

Another object of the invention is to provide, in a perforator of the character described, means for positively holding the cutter points in retracted position while lowering said perforator to the desired point in the well pipe, which means is releasable to permit operation of the perforator when desired.

A still further object of the invention is to provide an improved perforator of the character described having means for preventing the application of downward or longitudinal movement to the cutter points while said points are expanded in cutting position, whereby uniform perforations of the desired size are obtained, and also whereby fracture or breakage of the cutter points is eliminated.

Still another object of the invention is to provide, in a perforator of the type described, means for assuring the securing of the size and number of perforations desired, said means limiting penetration of the cutter points through the wall of the well pipe so that complete projection of all cutter points through said pipe is positively secured.

A particular object of the invention is to provide a perforator of the character described having anchoring means for locating said perforator at any desired elevation in the well pipe and also having means for positively securing perforations spaced from each other longitudinally of the well pipe any desired distance apart.

Another object of the invention is to provide a simple, positive, easily operable perforator which may be lowered into, operated and removed from the well pipe on a flexible wire or cable, and which forms tapered perforations in the well pipe, whereby plugging or clogging of such per-

forations by matter carried by fluids flowing therethrough is materially reduced.

Additional objects and advantages of the invention will be apparent from a reading of the following description of a device constructed in accordance with the invention, and reference to the accompanying drawings thereof, wherein:

Figure 1 is a view, partly in elevation and partly in section, of the upper portion of a perforator constructed in accordance with the invention and showing the same connected to wire line lowering device,

Figure 2 is a continuation of Figure 1, showing the lower portion of the perforator in position for being lowered into the well,

Figures 3 and 4 are views, partly in elevation and partly in section, showing the perforator in expanded perforating position within the well pipe,

Figure 5 is an enlarged horizontal cross-sectional view taken on the line 5—5 of Figure 4,

Figures 6 and 7 are enlarged horizontal cross-sectional views taken on the lines 6—6 and 7—7 respectively of Figure 2,

Figures 8 and 9 are similar views taken on the lines 8—8 and 9—9 respectively of Figure 4,

Figure 10 is a view, partly in elevation and partly in section, of a modified form of the invention, and

Figure 11 is a view, partly in elevation and partly in section, showing the device of Figure 10 revolved 90 degrees on its axis.

In the drawings, the numeral 15 designates an elongate cylindrical base member having a notch

35 16 formed in its upper end. Perforator knives 17 are pivotally secured within said notch by means of pins 18 which extend transversely of the notch through the base member and the lower ends of the knives. It is noted that the lower end of

40 each knife is rounded and pivots closely adjacent the bottom of the notch 17, so as to be additionally supported by the base member. The perforator knives are formed with long handle portions 19, and have chisel-pointed cutter points 20 extending laterally outward from the arms at their upper ends.

An elongate tubular sleeve 21 telescopes the perforator knives and the base member, and is slidably connected to said base member by means

50 of a key pin 22 mounted in the upper end of the base, said key having its ends engaging within longitudinal key slots 23 formed in the wall of the sleeve. The engagement of the key pin and slots serves to limit longitudinal movement between the base member and sleeve and to prevent

rotation of said base member within said sleeve. Elongate vertical windows or slots 24 are provided in the sleeve 21 and the cutter points 20 at the upper ends of the perforator knives are slidably longitudinally therein and expandable radially therethrough.

For expanding the cutter points 20, to drive them through the wall of the well pipe or tubing T, a cylindrical wedge member 25 is connected to the upper end of the sleeve 21 and extends downwardly therein. The wedge member has longitudinally extending inclined slots 26 formed on opposite sides thereof to provide inclined wedge surfaces 27 upon which the perforator knives are adapted to slide and be radially expanded, as is clearly shown in Figures 2 and 4. Obviously, as the wedge member and sleeve are moved downwardly with relation to the cutters or knives and base member, from the position shown in Figure 2 to the position shown in Figure 4, the inclined wedge surfaces 27 will expand the cutter points 20 radially outward through the windows 24 into engagement with the wall of the well tubing. Application of sufficient force to the wedge member will then drive the cutter points through the 25 tubing wall to form perforations therein.

The wedge member is forced downwardly by means of hammer blows delivered by manipulation of an ordinary weight member or sinker bar 28 and link jars 29 connected to the upper end 30 of the wedge member by screw-threads. The sinker bar and jars are manipulated within the well tubing by means of a flexible wire line or cable 30 connected to the upper end of the sinker bar by means of a suitable wire line socket 31. Obviously, lifting the sinker bar and jars to the position shown in Figure 1 and dropping them to the position shown in Figure 3, will impart a hammer blow to the wedge member 25 and force said wedge member downwardly between the perforator knives.

For holding the base member stationary to permit forcing the wedge member downwardly, an anchor or stop member S is connected by means of screw threads to the lower end of the base member.

The anchor includes an elongate mandrel 32 having a cylindrical portion 33 at its upper end. Immediately below the cylindrical portion the mandrel is tapered downwardly to form a slip expanding section 34, and an annular flange 35 is provided immediately below the slip expanding section. Below the flange 35 the mandrel has a reduced cylindrical shank 36, upon which a slip carrying collar 37 is freely slidable.

Gripping elements or slips 38 having sharp gripping teeth on their outer surface are slideable on the inclined slip expanding section 34 of the mandrel, and said elements have handles 39 depending therefrom. The slip handles extend downwardly through slots 40 formed in the flange 35, and are loosely connected to the slip carrying collar 37 by means of the engagement of their T-shaped lower ends 41 within correspondingly T-shaped slots 42 formed in the upper portion of the collar 37. The slip handles are restrained against outward displacement from the slots 42 by a band 43 which is secured in an annular groove surrounding said collar. A similar band 44 prevents outward displacement of the slip handles from the slots 40 in the flange 35.

The slip carrying collar 37 is slideable on the shank 36 and upward movement of the slips on the mandrel is limited by the engagement of said collar with the under side of the flange 35. En-

gagement of the slips with the upper surface of the flange prevents further downward movement of the slips on the mandrel.

As will readily be seen, normally the weight of the slips and the collar 37 will move said slips to their lowermost position on the mandrel, engaging the flange 35. However, downward movement of the mandrel with respect to the slips will move the inclined slip expanding section 34 downwardly between the slips to force said slips radially outward into gripping engagement with the wall of the tubing T. Such relative movement may be obtained by suddenly lowering the mandrel. Due to their inertia, the slips and collar will remain substantially stationary and the inclined section of the mandrel will move downwardly between the slips to immediately expand them to gripping engagement with the tubing.

Once the slips have engaged the wall of the well tubing, further application of downward force to the mandrel 32 tends to increase the gripping action of the slips. Thus, the anchor member is held stationary to support the base member 15 of the perforator so that the wedge member 25 may be driven downwardly to force the cutter points 20 radially outward through the wall of the well tubing to form perforations P therein, as shown in Figures 3 and 4.

The position in the well pipe at which the stop member S is set or anchored will ordinarily be determined by use of the customary measuring device (not shown) at the surface of the well for measuring the length of wire lowered into the well. Of course, any other suitable means might be used.

In lowering the perforator into the well pipe T, it has been found that it is desirable that the sleeve 21 and base member 15 be held in the extended position shown in Figures 1 and 2, whereby the perforator knives 17 are held retracted. In such position the wall of the sleeve at the lower end of the vertical windows 24 engages the outer edge of the knives to move said knives inwardly to retracted position. For readily holding the sleeve and base in such position, a shear pin 45 extends through said sleeve and base member just below the key pin 22. Obviously, the shear pin will hold the parts in this extended position until such time as said pin is fractured to permit the sleeve to telescope the base member. The pin 45 is readily sheared by jarring downwardly upon the wedge member 25 and sleeve 21 after the stop member S has been anchored in the well pipe. The shear pin may be readily renewed each time the perforator is used.

For positively indicating that the cutter points have been moved to their fully expanded position, and, hence, that said cutter points have penetrated the wall of the well pipe, an indicator pin 46 is secured within a transverse hole provided at the lower end of the base member. As is clearly shown in Figure 2, the outer ends of this indicator pin project radially beyond the surface of the base member. Thus, when the sleeve 21 has been moved to the position shown in Figure 4, the lower end of said sleeve will have sheared off the projecting ends of said indicator pin. Since the sleeve 21 is moved to its fully telescoped position (Fig. 4) when the wedge member 25 has been forced downwardly to the position at which the cutter points 20 are fully expanded, it will readily be seen that when the projecting ends of the indicator pin are sheared off the cutter points are indicated to have been fully expanded.

The cutter points are so dimensioned that,

upon full expansion, their outer points will extend beyond the normal outer diameter of the pipe and, therefore, complete penetration of the wall of the pipe is assured. Thus, disclosure that the cutter points have been fully expanded would indicate that the desired perforations have been made in the wall of the pipe.

It is noted that the cutter points 20 may be driven through the wall of the well pipe only until the handles 19 of the knives engage the pipe just below the cutter points. This engagement of the handles with the pipe prevents further penetration of the cutter points through the wall of the pipe. Thus, if one cutter point is driven through the wall of the pipe in advance of the other point, engagement of the handle of such advance knife with the wall of the pipe prevents further penetration of that point, and the opposite cutter is then forced through the wall of the pipe.

It will be seen, therefore, that the perforations formed by means of this perforator can never be larger than the size formed by such maximum penetration of the cutter points, and, also, that complete penetration of the wall of the pipe by both cutter points is assured.

When the wedge member 25 has been forced to its lowermost position, its lower end engages the upper end of the base member 15 and further downward movement of said wedge member and the sleeve 21 carried thereby is prevented. This prevents the sleeve at the upper ends of the windows 24 from engaging the upper ends of the perforator knives and forcing the cutter points downwardly, whereby breakage or shearing of the cutter points is prevented. Also, such engagement prevents unintentional longitudinal enlargement of the perforations such as might result from driving the cutter points downwardly while expanded, thus assuring the formation of uniform perforations of the desired size.

To remove the perforator from the well pipe T, the wire line 30 is lifted to elevate the sinker bar 28 and link jars 29. Upward movement of the jars moves the wedge member 25 and the sleeve 21 upwardly, and said sleeve engages the handles 19 of the perforator knives at the lower ends of the windows 24 to positively retract the cutter points 20 from the perforations P. Further upward movement of the wire line moves the parts of the perforator to the position shown in Figures 1 and 2, with the key pin 22 engaging the sleeve at the lower end of the key slot 23 to move the base member 15 upwardly. Upward movement of the base member raises the attached mandrel 32 of the stop member S from between the slips 38, permitting said slips to retract from gripping engagement with the wall of the well pipe. Continued upward movement then removes the entire device from the bore of the pipe.

A modified form of the invention is shown in Figures 10 and 11, wherein a stop member A is provided which is made separate from the perforator proper and is anchored within the well pipe in a slightly different manner from the stop member S of the first form.

As is clearly shown in Figure 10, the stop includes a mandrel 132 having an axial bore 50. Above the upper cylindrical section 33, the mandrel is formed with a retrieving neck 51 having an external undercut flange 52 at its upper end, and an upwardly facing annular shoulder 53 is formed between said retrieving neck and the cylindrical portion 33 of the mandrel. All 75

other parts of the stop A are identical with and bear the same numbers as the stop S first described.

The stop member A is lowered into the well pipe and anchored therein by means of a suitable lowering tool (not shown) which is connected to the lower end of the link jars. The lowering tool may be any of several suitable types on the market, and, of itself, forms no part of the invention.

The stop member is anchored within the well pipe by expanding the slips 38 into gripping engagement with the wall of the well pipe by moving the mandrel 132 downwardly between said slips, in the same manner as has already been described. When the stop has been anchored, the lowering tool (not shown) is released and removed from the bore of the pipe.

The base member 15 of the perforator has a 20 detachable and interchangeable skirt member 55 connected by screw threads to its lower end, and this skirt member is formed with a depending annular skirt 56 which engages over the retrieving neck 51 and is supported upon the shoulder 53 of the mandrel. All other parts of the perforator are the same and bear the same numbers as the perforator first described.

Since the skirt member 55 is supported on the shoulder 53 of the anchored stop member A, it is manifest that said skirt member supports the base member 15 of the perforator in a stationary position. Therefore, the wedge member 25 may be driven downwardly to force the cutter points of the perforator knives 17 through the wall of the pipe in the manner already set forth.

The length of the skirt member 55 may be varied as desired, so as to provide for spacing the perforations longitudinally within the pipe, and by definitely controlling the length of said skirt members the perforations may be as accurately spaced as the length of the skirt member is controlled. The stop member A remains set at the same location within the pipe while the perforator is removed and the skirt member changed, and, upon reinsertion of said perforator in the pipe to its position on the stop member, definite spacing of the perforations at that elevation in the well is assured. Thus, a plurality of uniform perforations, spaced at desired elevations in the well pipe, may be readily secured by removing the perforator and changing the skirt section.

After the tubing has been perforated, the perforator is removed from the pipe and a suitable removing or retrieving tool (not shown) is lowered into the bore of said pipe to engage and pull the stop member A from the well. The retrieving tool (not shown) may be one of several types on the open market suitable for the purpose.

Due to the chisel-point shape of the cutter points 20, the perforations P formed thereby are flared outwardly as they extend inwardly from the outer periphery of the pipe, and plugging or clogging of such perforations by solid matter carried by the fluids flowing therethrough is prevented. Any matter which enters the small outer portion of the perforations will readily pass through the larger inner portion thereof.

Manifestly, a perforator has been provided which may be lowered into a well pipe and operated therein to form perforations in its wall by means of a flexible line or cable. Such perforator will also form uniform perforations at a

definite desired location in said pipe. Further, means has been provided for indicating whether or not perforations have been formed in the wall of the pipe as desired. The perforator also has means for preventing breakage of the cutter points, both during lowering and during perforating. Moreover, means has been provided for positively and accurately spacing perforations at a plurality of levels within the well pipe. Likewise, the perforator may be used with various suitable types of stop members, either attached to the perforator or independently anchored within the well pipe.

It is particularly to be noted that the perforators are adapted to be lowered into, operated in and removed from a well pipe "under pressure," that is, in wells wherein the well fluid pressure is present within said pipe during said operations. For such use, the flexible line 30 would be a solid steel wire measuring line, common to the oil fields, and the perforator would be lowered into the well pipe with the upper end of said pipe closed by a stuffing box (not shown) which would seal around the solid steel line to prevent escape of the well pressure fluids.

The above description of the invention is explanatory only, and changes in details of the constructions illustrated may be made by those skilled in the art, within the scope of the appended claims, without departing from the spirit of the invention.

What I claim and desire to secure by Letters Patent is:

1. A well pipe perforator including, a base member having means for releasably anchoring it in a stationary position within a well pipe, elongate perforator means having its lower end swingably supported by the base member and having a perforating element at its upper end, an expanding member for engaging the upper end of the perforator means to move the perforating element to perforating position, and a sleeve member telescoping the perforator means and base member and having means for positively retracting the perforator element from perforating position.

2. A well pipe perforator including, a base member, releasable means engageable with the wall of a well pipe for positively anchoring said member in a stationary position at any desired level in said well pipe, perforator means supported by said base member, and means for forcing said perforator means outwardly through the wall of the well pipe to form perforations therein, said forcing means engaging the base member to limit the application of outward force to said perforator means by said forcing means.

3. A well pipe perforator including, a base member, perforator means supported by the base member, means for forcing the perforator means outwardly through the wall of a well pipe to form perforations therein, and anchoring means for engaging the wall of the well pipe to positively support the base member at any desired level in the well pipe to permit formation of perforations at such level, said anchoring means being releasable and movable either upwardly or downwardly from the level of the original perforations to a new level for supporting said base member to permit perforating at such new level.

4. A well pipe perforator including, a base member, anchoring means for supporting said base member at any desired level within a well pipe, movable perforator cutters carried by the base member, forcing means for expanding said

cutters to form perforations in the wall of the well pipe, and frangible means for preventing said forcing means from prematurely expanding the perforator cutters.

5. A well pipe perforator including, a member having means for anchoring it in a stationary position in a well pipe, perforator elements supported by said member, means operable to force the perforator elements outwardly through the wall of the well pipe to form perforations therein, and a member engageable by said forcing means providing positive recording means for indicating that the perforator elements have been forced outwardly sufficiently to form such perforations.

15 6. A well pipe perforator including, a member having releasable means engageable with the wall of a well pipe, means for anchoring it in a stationary position in said well pipe, perforator elements supported by said member, means operable to force the perforator elements outwardly through the wall of the well pipe to form perforations therein, and means interposed between the support member and perforator elements providing for positively spacing perforations at 20 a plurality of levels longitudinally within the well pipe.

25 7. A well pipe perforator including, a base member having means for anchoring it in a stationary position within a well pipe, elongate perforator knives having their lower ends pivotally secured to and supported by said base member, a wedge member having inclined surfaces upon which the upper ends of the perforator knives are slidable so as to be expanded to perforating 30 position thereby, and a sleeve member telescoping the perforator knives and having means for positively retracting said knives from perforating position.

35 8. A well pipe perforator including, a base member having means for anchoring it in a stationary position within a well pipe, elongate perforator knives having cutter points at their upper ends and having their lower ends pivotally secured to and supported by said base member, a wedge member having inclined surfaces 40 upon which the upper ends of the perforator knives are slidable so as to be expanded to perforating position thereby, a sleeve member telescoping the perforator knives and having windows through which the cutter points of said 45 knives are expandable, means for positively retracting said knives from perforating position, and means for releasably holding said perforator knives in retracted position.

50 9. A well pipe perforator including, a base member having means for anchoring it in a stationary position within a well pipe, elongate perforator knives having cutter points on their upper ends and having their lower ends pivotally secured to and supported by the base member, a wedge member having inclined surfaces 55 upon which the upper ends of the knives are slidable so as to be expanded to perforating position thereby, and means for indicating that the cutter points have been sufficiently expanded to form the desired perforations.

60 10. A well pipe perforator including, a base member, means for anchoring said base member in a stationary position within a well pipe, elongate perforator knives having cutter points at their upper ends and having their lower ends pivotally secured to and supported by the base member, and a wedge member having inclined surfaces upon which the upper ends of the knives 65 are slidable and movable toward the base mem-

ber to expand the cutter points to perforating position, said wedge member being arranged to abut the upper end of the base member to limit the application of outward force upon the cutter points and to prevent the application of downward force to said cutter points.

11. A well pipe perforator including, a base member, elongate perforator knives having cutter points on their upper ends and having their lower ends pivotally secured to and supported by said base member, a wedge member having inclined surfaces upon which the upper ends of the perforator knives are slidable so as to be expanded to perforating position thereby, and anchoring means for supporting the base member in a stationary position at any desired level in a well pipe to permit perforating the wall of such pipe at that level, said anchoring means being movable upwardly or downwardly from the level of the original perforations to a new level for supporting said base member to permit perforating at such new level.

12. A well pipe perforator including, a base member, elongate perforator knives having cutter points on their upper ends and having their lower ends pivotally secured to and supported by said base member, a wedge member slidably connected to the base member and having inclined surfaces upon which the upper ends of the perforator knives are slidable so as to be expanded to perforating position thereby, and separate anchoring means for supporting the base member in a stationary position at any desired level within a well pipe to permit perforating the wall of the pipe at such level, said anchoring means being removable from the well pipe.

13. A well pipe perforator including, a base member, elongate perforator knives having cutter points on their upper ends and having their lower ends pivotally secured to and supported by said base member, a wedge member slidably connected to the base member and having inclined surfaces upon which the upper ends of the perforator knives are slidable so as to be expanded to perforating position thereby, separate anchoring means for supporting the base member in a stationary position at any desired level within a well pipe to permit perforating the wall of said pipe at such level, and detachable and interchangeable spacer means carried by the base member and interposed between said base member and the anchoring means for positively spacing perforations at a plurality of levels longitudinally within the well pipe.

14. A well pipe perforator including, a base member, means for anchoring said member at any desired level within a well pipe, elongate perforator knives having cutter points at their upper ends and having their lower ends pivotally secured to and supported by the base member, a wedge member slidably connected to the base member and having inclined surfaces upon which the upper ends of the knives are slidable and movable toward the base member to expand the cutter points to perforating position, a sleeve member carried by the wedge member and tele-

scoping the perforator knives and having windows through which the cutter points of said knives are expansible, means on the sleeve for engaging the knives to retract the same from perforating position upon upward movement of said sleeve, means for releasably holding said sleeve in position retracting said perforator knives, and means carried by the base member for indicating that the cutter points have been sufficiently expanded to perforate the wall of the well pipe.

15. A well pipe perforator including, a base member, means for anchoring said base member at any desired level within a well pipe, elongate perforator knives having cutter points at their upper ends and having their lower ends pivotally secured to and supported by the base member, a wedge member slidably connected to the base member and having inclined surfaces movable toward the base member for expanding the cutter points to perforating position, said wedge member being adapted to engage the upper end of the base member to prevent downward movement of the cutter points and limit the outward expansion thereof, a sleeve carried by the wedge member and telescoping the perforator knives, means on said sleeve for positively retracting said knives upon movement of said sleeve away from the base member, and means for releasably holding the sleeve in position retracting said perforator knives.

16. A well pipe perforator including, a base member having releasable means for engaging the wall of a well pipe to anchor it in a stationary position within said pipe, elongate perforator knives having projecting cutter points on their upper ends and having their lower ends swingably supported by the base member, a wedge member for engaging and expanding the upper ends of said knives, said knives having an upper portion adapted to engage the wall of the well pipe to prevent excessive penetration of such wall by the cutter point thereon, whereby when any one cutter point has fully penetrated the wall of the pipe the engagement of such upper portion with said wall provides a stop and support to cause the wedge member to force the other cutter points outwardly through the wall of the pipe to assure perforation thereof by all cutter points.

17. A well pipe perforator including, a base member having means for releasably anchoring it in a stationary position within a well pipe, elongate perforator means having its lower end swingably supported by the base member and having a perforating element at its upper end, an expanding member for engaging the upper end of the perforator means to move the perforating element to perforating position, a sleeve member carried by the expanding member and telescoping the perforator means and base member and having means for positively retracting the perforator element from perforating position, and recording means engageable by said sleeve for positively indicating that said perforator element has been fully expanded.

JOHN C. LUCCOUS.
